No. 36,918.

Patented May 17, 1904.

UNITED STATES PATENT OFFICE.

FRANCIS J. TORRANCE, OF ALLEGHENY, PENNSYLVANIA.

DESIGN FOR A LAVATORY.

SPECIFICATION forming part of Design No. 36,918, dated May 17, 1904.

Application filed November 17, 1902. Serial No. 131,784. Term of patent 14 years.

To all whom it may concern:

Be it known that I, FRANCIS J. TORRANCE, a citizen of the United States, residing at Allegheny, in the county of Allegheny and State 5 of Pennsylvania, have invented a new, original, and ornamental Design for Lavatories.

My design for a lavatory is shown in the accompanying drawing, which is a perspective view of the same.

What I claim, and desire to secure by Letters Patent, is—

The ornamental design for a lavatory herein shown.

FRANCIS J. TORRANCE.
